UNITED STATES PATENT OFFICE.

WILLIAM C. CARTER, OF ST. LOUIS, MISSOURI.

DIAPHRAGM-PUMP.

1,191,061.

Specification of Letters Patent. Patented July 11, 1916.

Application filed December 7, 1914. Serial No. 875,942.

To all whom it may concern:

Be it known that I, WILLIAM C. CARTER, a citizen of the United States, residing at St. Louis, Missouri, have invented a certain 5 new and useful Improvement in Diaphragm Pumps, of which the following is a full, clear, and exact description, such as will enable others skilled in the art to which it appertains to make and use the same.

10 This invention relates primarily to diaphragm pumps, although one feature of my invention consists in a fuel supply device of novel design that is similar in construction and principle of operation to the fuel supply apparatus disclosed in my prior Patent 15 No. 1,146,133, dated July 13, 1915.

One object of my present invention is to provide a diaphragm pump which is so designed that the diaphragm chamber of the 20 pump will be absolutely cut off from the pressure line after the diaphragm has moved in one direction, thereby preventing the diaphragm from being subjected to abnormal pressure after it has performed its function.

25 Another object is to provide a diaphragm pump that is equipped with a valve, controlled by the diaphragm that closes automatically, and thus cuts off communication between the diaphragm chamber of the 30 pump and the pressure line after pressure sufficient to actuate the diaphragm has entered the diaphragm chamber.

Another object is to provide a diaphragm pump which is so constructed that when it 35 is used in connection with an internal combustion engine the force of the explosions and the hot gases and carbon will not act upon or come in contact with the diaphragm of the pump.

40 Another object is to provide a diaphragm pump in which the diaphragm is so constructed that it will not break or lose its resiliency after long service. And still another object of my invention is to provide 45 a fuel supply device for internal combustion engines which is of novel construction.

Figure 1 of the drawings is a vertical sectional view of a fuel supply device and diaphragm pump constructed in accordance 50 with my invention. Fig. 2 is a detail sectional view taken on the line 2—2 of Fig. 1; and Fig. 3 is a detail view, illustrating a slight modification of my invention.

55 Referring to Fig. 1 of the drawings which illustrates the preferred form of my invention, A designates the casing of my im-

proved pump, which is preferably formed from two disk-shaped members whose peripheral edge portions are securely connected together in any suitable manner, as, for example, by means of rivets 1. The space inside of the casing A, which I will term the diaphragm chamber, is divided into two compartments by means of a diaphragm B that consists of a disk-shaped member whose peripheral edge portion is securely clamped between the two members that constitute the casing A of the pump. One side of the casing A communicates with a pressure line 2 in which the pressure rises and falls intermittently, and the other side of said casing communicates with a device that the pump operates. I have herein illustrated my improved pump as being used in connection with an internal combustion engine for 75 drawing a charge of liquid fuel from a source of supply and forcing it into a tank or reservoir from which the liquid fuel is conducted to the carburetor of the engine, but I wish it to be understood that the pump 80 is not limited to this use or to use with an internal combustion engine, for it can be used for various other purposes and in connection with any kind of a compressing device or pressure line in which the pressure 85 rises and falls intermittently, and thus causes the diaphragm of the pump to vibrate back and forth.

In the apparatus herein shown the pressure line 2 that communicates with one side 90 of the diaphragm chamber of the pump leads to one of the cylinders of an internal combustion engine or to the exhaust pipe of the engine, not shown, and the opposite side of said diaphragm chamber communicates with a valved passageway that is arranged between a liquid fuel supply pipe 3 and a tank or reservoir C which is provided at its lower end with a discharge pipe 4 that leads to the carburetor of the engine. 100 When the diaphragm B of the pump moves in one direction a check valve 5 that acts as the inlet valve for said passageway will open automatically, and thus permit liquid fuel to be drawn into said passageway from the supply pipe 3 by the suction created in said passageway, by the movement of the diaphragm of the pump. When the diaphragm of the pump moves in the opposite direction this charge of fuel that was 105 drawn into the valved passageway by the preceding movement or suction stroke of

the diaphragm will be forced out of said passageway into the fuel tank C through a discharge port that is normally closed by a discharge valve 6.

- 5 In the diaphragm pumps that have heretofore been in general use, so far as I know, the diaphragm chamber was either in direct communication with the pressure line that operated the pump or a gravity-operated 10 valve provided with an inlet opening was arranged between the diaphragm chamber and the pressure line. Consequently, when such pumps were used in connection with internal combustion engines the diaphragms 15 were soon rendered unfit for use, by reason of the high pressure and the hot gases and the carbon coming in direct contact with the diaphragms, this, of course, being due to the fact that the diaphragms were subjected 20 to the direct action of the explosions in the engine. In order to overcome this objectionable feature I have provided my improved pump with means controlled by the diaphragm for cutting off communication 25 between the diaphragm chamber and the pressure line after sufficient pressure has entered the diaphragm chamber to move the diaphragm in one direction. When the pump is used in connection with an internal 30 combustion engine said means prevents the diaphragm from being subjected to the direct action of the explosions in the engine, and it also prevents the hot gases and carbon from coming in contact with the diaphragm. Furthermore, it prevents the diaphragm from being subjected to abnormal 35 pressure, this being true whether the pump is used in connection with an internal combustion engine or with any other type of compressing device. The means that I prefer to use for accomplishing this consists 40 of a valve D arranged between the pressure line 2 and the diaphragm chamber of the pump and constructed in such a manner that it will be held in its open position by the diaphragm and will close automatically 45 before the pressure in the pressure line 2 reaches a high degree. Said valve D is provided with a stem 7 that passes loosely 50 through a port in a valve casing 8 that is connected to one side of the casing A of the pump, the valve casing 8 of the pump herein shown being provided with a reduced screw-threaded portion 8^a that is screwed 55 into one side of the pump casing at the center of same. The stem 7 of the valve D is provided with one or more longitudinally extending grooves 7^a that establish communication 60 between the pressure line 2 and the diaphragm chamber of the pump when the valve D is open. Said valve stem 7 is preferably so proportioned that when the valve D is seated, as shown in Fig. 1, the inner end of the stem 7 will bear lightly upon the 65 diaphragm B of the pump. In the embodiment

of my invention herein shown the diaphragm is imperforate, or, in other words, is not provided with an orifice through which a gas or liquid could pass from one side of the diaphragm to the other side of the diaphragm and the valve stem 7 is not rigidly connected to the diaphragm, thus producing a pump that is particularly well adapted for pumping gasoline and other volatile liquids. When the diaphragm is flexed in one direction it bears against the inner end of the stem 7 and thus holds the valve D unseated so that the pressure can enter the diaphragm chamber quickly and actuate the diaphragm. When the pressure flexes the diaphragm in the opposite direction, the valve D follows the diaphragm and moves to its closed position. The outward movement of the valve D is limited by means of a stop 9, against which the head of the valve D strikes when said valve is moving to its open position. The diaphragm B is moved in one direction, to the left, looking at Fig. 1, by the pressure in the pressure line 2, and said diaphragm B is moved in the opposite direction by means of a spring 10 that is arranged inside of a nipple 11 which projects laterally from one side of the casing A of the pump, the diaphragm B being preferably provided with a boss or projection 12 that tends to center the spring 10 and cause it to bear evenly upon the diaphragm B of the pump.

When the engine is in operation the diaphragm B vibrates back and forth in the manner previously described, the movement of said diaphragm to the right, looking at Fig. 1, being effected by the spring 10, and the movement of said diaphragm to the left being effected by the pressure in the pressure line 2. When the diaphragm B moves to the right, under the influence of the spring 10, the pressure that it exerts against the stem of the valve D causes said valve to open. Said valve remains in its open position, due to the pressure that the diaphragm exerts thereon, during the first portion of the compression stroke of the piston of the particular cylinder of the engine to which the pressure line 2 leads. The pressure that is developed in the pressure line 2 during the first part of the compression stroke of the piston is exerted on the diaphragm B of the pump, and consequently, will impart a power impulse to said diaphragm, or, in other words, cause it to move to the left, looking at Fig. 1, it, of course, being understood that at this time the grooves or grooves 7^a in the stem of the valve D, which is open, establish communication between the pressure line 2 and the diaphragm chamber of the pump and permit sufficient pressure to enter said chamber to actuate the diaphragm quickly. When the pressure in the pressure line 2 reaches a certain degree

the valve D will close, and thus completely cut off communication between the diaphragm chamber of the pump and the pressure line 2. The groove or grooves 7^a in the 5 stem of the valve D are so proportioned that said valve will move at such a speed that it will be closed by the time the diaphragm B has reached its limit of movement to the left. In other words, the groove or grooves 7^a in 10 the stem of the valve D are just large enough so that only sufficient pressure to actuate the diaphragm will enter the diaphragm chamber of the pump before the valve D closes, the subsequent rise in pressure 15 in the pressure line 2 having no effect upon the diaphragm B, in view of the fact that the diaphragm chamber is then absolutely cut off from the pressure line. When the pressure in the line 2 drops, the spring 20 10 moves the diaphragm B of the pump in the opposite direction and also restores the valve D to its open position. From the foregoing it will be seen that the valve D closes before the explosion in the cylinder 25 of the engine occurs and remains closed until the pressure in the line 2 drops or diminishes sufficiently to permit the spring 10 to restore the diaphragm to its normal position. Consequently, the diaphragm of the 30 pump is not subjected to the direct force of the explosion in the engine, and there is no possibility of the hot gases and carbon coming in direct contact with same, and thus damaging or destroying the diaphragm. 35 The diaphragm B of the pump may be formed in various ways and from any suitable material. It is preferably built up of several layers of sheet material so as to form a laminated diaphragm. One type of 40 diaphragm that I have found to be very efficient is made from a single sheet of fibrous or non-metallic material *a* arranged between two thin sheets of copper or other suitable material *b*, as shown in Fig. 1, the 45 fibrous material that I prefer to use being known commercially as "Seigelite" and consisting of a woven fabric that is not affected by gasolene. The fiber *a* will not break or lose its elasticity, even after it has been subjected to long continuous use and the layers 50 or sheets of metal *b* that incase the fiber protect same from any moisture that might enter the diaphragm chamber, and thus cause the fiber to warp if it were not protected, the layers of sheet metal *b* that cover the fiber being sufficiently thin so that they 55 will not be broken by the constant vibrations of the diaphragm back and forth.

In Fig. 3 I have illustrated another type 60 of diaphragm that I have also found to be very efficient, and which consists of a plurality of layers of relatively thin sheet metal *c* clamped together and arranged in such a manner that the grain in the metal of one 65 sheet or layer crosses the grain of the metal

in the other sheets or layers between which it is arranged.

The complete fuel supply device, of which my improved pump forms a part, is of novel design, in that a spring 6^a is employed for 70 normally holding the discharge valve 6 seated, and means are provided for closing the air vent opening 13 at the upper end of the fuel reservoir C when the fuel in said reservoir rises above a certain level, due to 75 the pressure that the source of supply exerts on the fuel in the reservoir C when the automobile on which the device is used is traveling down an incline. A float 14 that is arranged inside of the fuel reservoir C is securely connected to a rod 15 whose lower end projects into a hollow valve stem 6^b on the discharge valve 6, said rod being provided with a head 16 that strikes against the upper end of the valve stem 6^b, and thus raises said 80 valve from its seat when the fuel in the reservoir C rises above a certain level. A spider or stop 17 that is connected to the rod 15 forms a stop or abutment for the upper end of the valve spring 6^a, and thus causes said 85 spring to exert sufficient tension on the valve 6 to hold same closed, even though the float 14 rises and falls as the level of the fuel in the tank C varies. The upper end of the rod 15 supports a ball check valve 18 that moves 90 upwardly and closes the air vent 13 when the source of supply of liquid fuel becomes arranged in a higher horizontal plane than the valves that govern the admission of fuel into the reservoir C. At such times the pressure that the source of supply exerts on the fuel in the reservoir C is sufficient to cause the fuel to flow from said reservoir to the carbureter through the discharge pipe 4 at 95 the lower end of the reservoir C. Normally 100 the air vent 13 is open, even when the float 14 rises high enough to unseat the discharge valve 6 and cut off the supply of fuel to the reservoir from the passageway between the valves 5 and 6, because the distance between the head 16 on the rod 15 and the upper end of the valve stem 6^b is less than the distance 105 between the check valve 18 and its seat. In other words, the float 14 can rise high enough to unseat the valve 6 and cause the 110 supply to the reservoir C to be cut off without causing the air vent 13 to be closed. It is only when the source of supply of fuel is arranged in a higher level than the valves 5 and 6 that the float 14 will rise high enough 115 to cause the valve 18 to close the air vent 13, but as the supply of fuel is then exerting pressure on the fuel in the reservoir, the fuel can flow freely from the reservoir to the carbureter.

Having thus described my invention, what I claim, and desire to secure by Letters Patent, is:

1. A diaphragm pump provided with an imperforate diaphragm that is adapted to be 130

5 moved in one direction by the pressure in a
6 pressure line, a housing in which said dia-
7 phragm is arranged, one side of said hous-
8 ing communicating with a chamber or pas-
9 sage way through which the material being
10 pumped passes, and means controlled by the
diaphragm for preventing the diaphragm
from being subjected to greater pressure
than that which was required to move it
11 after said diaphragm has moved in one di-
12 rection.

13 2. A diaphragm pump provided with an
imperforate diaphragm and with means con-
14 trolled by the diaphragm for preventing the
15 supply of pressure that operates the dia-
phragm from entering the diaphragm cham-
16 ber of the pump after the diaphragm has
been moved in one direction.

17 3. A diaphragm pump provided with a
18 diaphragm chamber, one side of which has
19 an opening that communicates with a pres-
20 sure line in which the pressure rises and
21 falls intermittently and the other side com-
22 municating with a passageway through
23 which the material being pumped passes, an
imperforate diaphragm in said chamber, and
24 means controlled by the diaphragm for
25 absolutely cutting off communication be-
26 tween said diaphragm chamber and pressure
27 line after the diaphragm has been moved in
28 one direction by the pressure in said line.

29 4. A diaphragm pump that is adapted to
30 be operated by an expansible medium, said
31 pump being provided with means controlled
32 by the diaphragm for causing the supply of
33 expansible medium that actuates the dia-
34 phragm to be absolutely cut off from the
35 diaphragm chamber of the pump after said
36 diaphragm has been moved in one direction,
37 said means consisting of an element separate
38 and distinct from the diaphragm and which
39 can move independently of the diaphragm.

40 5. In a diaphragm pump that is adapted
41 to be operated by an expansible medium, an
imperforate diaphragm, and a valve that is
42 held in its open position by the diaphragm,
43 said valve being arranged between the dia-
44 phragm and the supply of pressure that op-
45 erates the diaphragm and being adapted to
46 be closed automatically by said pressure
47 after the diaphragm has been moved in one
48 direction by the pressure which entered the
49 diaphragm chamber of the pump.

50 6. A diaphragm pump, comprising a cas-
51 ing, a diaphragm arranged inside of same, a
52 spring arranged on one side of said dia-
53 phragm for moving it in one direction,
54 means whereby an expansible medium will
55 act upon said diaphragm to move it in the
56 opposite direction, and means governed by
57 said diaphragm for cutting off communica-
58 tion between the diaphragm and the source
59 of supply of said expansible medium after
60 said diaphragm has been moved by said ex-
61 pansible medium.

62 7. A diaphragm pump provided with a
63 diaphragm which is adapted to be moved in
64 one direction by the pressure of an expansible
65 medium, a valve arranged between the dia-
66 phragm and the supply of expansible 70
67 medium that actuates said diaphragm, said
68 valve being held in its open position by said
69 diaphragm and being adapted to close auto-
70 matically and thus cut off communication
71 between the diaphragm chamber of the 75
72 pump and the pressure line after the dia-
73 phragm has been moved by said expansible
74 medium, and a spring for moving said dia-
75 phragm in the opposite direction and for
76 opening said valve. 80

77 8. A diaphragm pump provided with an
imperforate diaphragm, a pressure line for
78 supplying pressure to operate the dia-
79 phragm, an imperforate valve that is ar-
80 ranged between the diaphragm of the pump 85
and said pressure line and which is held in
81 an inoperative position by the diaphragm,
82 said valve being adapted to move independ-
83 ently of the diaphragm and being so con-
84 structed that it will be closed automatically 90
85 by the pressure in said line and thus cut off
86 all communication between said pressure
87 line and the diaphragm after the diaphragm
88 has moved in one direction.

89 9. In a diaphragm pump of the type that 95
is adapted to be operated by the pressure of
90 an expansible medium supplied through a
91 pressure line, an imperforate diaphragm, an
imperforate pressure-operated valve that is
92 arranged between the diaphragm and the 100
93 pressure line that operates the pump so as
94 to cut off communication between said dia-
95 phragm and pressure line, a part provided
96 with a port, and a stem on said valve loosely
97 mounted in said port and being so con-
98 structed that the pressure can pass through
99 said port and actuate the diaphragm before
100 the pressure in said line becomes great
101 enough to cause said valve to close, the inner
102 end of said stem normally bearing against 105
103 one side of the diaphragm. 108

104 10. A diaphragm pump provided with a
105 pressure supply passageway, an imperforate
106 valve for cutting off all communication be-
107 tween said passageway and the diaphragm 115
108 chamber of the pump, an imperforate dia-
109 phragm in said chamber, a stem on said
110 valve arranged in said passageway and bearing
111 against one side of the diaphragm of
112 the pump, and means whereby the pres-
113 sure can pass through said passageway into
114 the diaphragm chamber of the pump and
115 operate the diaphragm before the pressure
116 in said passageway becomes great enough to
117 cause said valve to close. 120

116 11. A diaphragm pump provided with an
imperforate valve for cutting off all com-
117 munication between the diaphragm chamber
118 of the pump and the pressure line that op-
119 erates the pump, said valve being moved to 130

its closed position by the pressure in said line, a spring for opening said valve, and a diaphragm which permits the valve to close when said diaphragm moves in one direction.

5 12. A diaphragm pump provided with an imperforate valve for absolutely cutting off communication between the diaphragm chamber of the pump and the pressure line 10 that operates the pump, said valve being moved to its closed position by the pressure in said line, means for opening the valve, means for limiting the opening movement of the valve, and an imperforate diaphragm 15 that governs the closing of said valve.

13. A diaphragm pump comprising a casing, an imperforate diaphragm arranged inside of said casing, one side of said casing communicating with a pressure line, and an 20 imperforate pressure-operated valve arranged between said diaphragm and pressure line and provided with a stem whose inner end bears against one side of the diaphragm, thereby causing the diaphragm to govern the 25 closing of the valve, said valve being so constructed that it will close automatically and thus cut off communication between the diaphragm and pressure line when the pressure in said line reaches a certain degree after 30 the diaphragm has been flexed in one direction.

14. A diaphragm pump, comprising a casing, a diaphragm arranged inside of said casing, one side of said casing communicating with a pressure line, an imperforate valve arranged between said diaphragm and pressure line and provided with a stem whose inner end bears against the diaphragm so that the diaphragm will govern the opening and closing of said valve, 35 said valve being so constructed that it will close automatically and thus cut off communication between the diaphragm and pressure line when the pressure in said line reaches a certain degree after the diaphragm 40 has been moved in one direction, and a

spring arranged on the opposite side of the diaphragm that restores the diaphragm after it has been actuated by the pressure in said line, and which also causes the valve 50 to move to its open position.

15. A diaphragm pump provided with a diaphragm formed from a sheet of fibrous material, and sheets of metal arranged on opposite sides of said fibrous material so as 55 to protect same.

16. A fuel supply device, comprising a liquid fuel tank, a valved passageway arranged between said tank and a source of supply of liquid fuel, an inlet valve for said 60 passageway for controlling the admission of the liquid fuel into same, an outlet valve for said passageway for controlling the flow of the liquid fuel into said tank, a spring that normally holds said outlet valve seated, 65 and means for automatically unseating said outlet valve.

17. A fuel supply device for internal combustion engines provided with a liquid fuel tank, a valved passageway arranged intermediate said tank and a supply of liquid fuel, said passageway being provided with an inlet valve that governs the admission of the liquid fuel to said passageway and also having a discharge valve that governs 70 the flow of the fuel from said passageway into said tank, a spring that normally exerts pressure on said discharge valve, a float in said tank, a device governed by said float that unseats said discharge valve automatically when the fuel in said tank rises above a certain level, and means on said device that forms an abutment for the spring which holds said discharge valve seated.

In testimony whereof I hereunto affix my 85 signature in the presence of two witnesses, this third day of December, 1914.

WILLIAM C. CARTER.
